ELECTRIC CONTROL SYSTEM

Andrew J. Sorensen, Edgewood, Pa., assignor to
The Union Switch & Signal Company, Swiss-
vale, Pa., a corporation of Pennsylvania

Application August 10, 1932. Serial No. 628,163

11 Claims. (Cl. 246—63)

My invention relates to electric control systems, and particularly to electric control systems for governing the operation of railway trains.

I will describe certain forms of apparatus embodying my invention, and will then point out the novel features thereof in claims.

In the accompanying drawings, Figs. 1 and 2 when taken together constitute a diagrammatic view of one form of apparatus embodying my invention when applied to a communicating and brake control system for a railway train. The apparatus of Fig. 1 is that located at the control point, which, in this instance, is on the locomotive. The apparatus of Fig. 2 is that installed at another point on the train. While the apparatus of Fig. 2 may be located at any point on a train, it will be considered in this description as being in the caboose of a freight train. Fig. 3 is a diagrammatic view of a modified form of apparatus that may be used at the control point or at the second point on the train for selectively receiving the different control and signaling influences.

The apparatus of Fig. 1 is adapted to transmit a different control influence for each of several different functional positions of the engineer's brake valve and also to transmit at times signaling influences. Furthermore, this apparatus of Fig. 1 is capable of receiving indication and signaling influences for causing the display of indicating and signaling devices. The apparatus of Fig. 2 is adapted to receive the different control influences transmitted by the apparatus of Fig. 1 for causing an auxiliary brake controlling mechanism to reproduce the functions of the usual engineer's brake valve on the locomotive. The apparatus of Fig. 2 is also capable of transmitting an indication influence and to receive and transmit signaling influences. These control, indication and signaling influences are preferably in the form of coded modulated carrier current, the impulses of which are preferably transmitted between the locomotive and the caboose through the medium of the traffic rails in a manner disclosed and claimed in the L. O. Grondahl application for United States Letters Patent, Serial No. 450,135, filed May 6, 1930, for Electric train signaling systems.

Two methods have found general use for obtaining a carrier current modulated at a lower frequency. One method is to generate a carrier frequency current and a modulation frequency current separately and then combining the two, while the other method is to generate two different carrier currents having a frequency dif-

ference equal to the modulation frequency desired and then combining the two carrier currents. In systems using the latter method, it is evident that since the frequency of the modulation depends on the difference between the two carrier currents, the frequencies of these carrier currents must be controlled to a very high degree of accuracy to avoid too great a variation of modulation frequency. A feature of my invention is the provision of novel and improved apparatus for electric control systems of the type here involved wherein a relatively large variation can be tolerated in the frequencies of two carrier currents employed for obtaining a modulation frequency.

Referring to Fig. 1, the engineer's brake valve EV is of any of the well-known types capable of establishing several train brake controlling conditions, usually release, running, lap, service and emergency. As shown schematically, the contact members 4 and 5 are connected to and actuated by the handle 3 of the brake valve EV. The contact member 4 is adapted to engage a contact segment 6 in the service position of the handle 3 only. The contact member 5 is adapted to engage a contact segment 7 in both the release and running positions of handle 3, and to engage a contact segment 8 in both the lap and service positions of handle 3. The functions of this contact assembly associated with the brake valve EV will appear as the description progresses.

The locomotive is provided with two coders designated by the reference characters N1 and N2. Although these coders may be any one of many types a preferred type is that known as the mechanically tuned type such, for example, as is disclosed in the United States Letters Patent, No. 1,858,876, issued May 17, 1932, to Paul N. Bossart, for Coding apparatus, and it is deemed sufficient for the purpose of this application to describe these coders only in a general way. Referring to coder N1, a field structure J is provided with two pole pieces P1 and P2, between which there is mounted, so as to swing freely, an armature H pivoted at O. The armature H is biased to a mid-position between the poles P1 and P2, that is, to the position as shown in Fig.

1. In this mid-position, a contact member 9 actuated by the armature H engages a contact 10. A field winding 60 is connected to a current source such as a battery 11 by a simple circuit that includes the contact 10 and the contact member 9 as will be readily understood by an inspection of Fig. 1. The energizing of the field winding 60 of coder N1 causes its armature H to

rotate in a clockwise direction as indicated by an arrow. After a slight movement of the armature H the contact member 9 becomes disengaged from the contact 10 and the field winding 60 is deenergized. The armature H will rotate a little farther and then due to its bias, will reverse its movement until the contact 10 is again closed and the field winding 60 reenergized. During the movement of the armature H after the contact member 9 disengages the contact 10, the contact member 9 engages a second contact 12. The biasing force and the weight of the armature H of coder N1 are made such that it will have a natural period of say sixty cycles per minute, at which frequency it will oscillate as long as current is supplied to its field winding 60 by the circuit that includes its own contact member 9. It follows, that the contact member 9 of coder N1 will be oscillated between the two contacts 10 and 12 at the code frequency of sixty cycles per minute. The coder N2 is similar to coder N1 except that its biasing force and the weight of its armature are made such that it has a natural period of say one hundred cycles per minute at which frequency its contact member 13 will be oscillated between the two contacts 14 and 15 as long as its field winding 100 is supplied with current from the battery 11 by the circuit that includes its own contact member 13 and the contact 14.

Associated with these two coders N1 and N2 is a relay 16 which is supplied with current from the battery 11 by any one of three separate circuits. A first circuit for the relay 16 can be traced from the battery 11 through winding of relay 16, the upper and normally closed contact 17 of a manually operated signaling key K1, contact 12 of coder N1, contact member 9 and back to the opposite terminal of battery 11. With the signaling key K1 depressed to bring the contact member 17 to the position indicated by dotted lines in the drawings, a second circuit for relay 16 can be traced from battery 11 through winding of relay 16, contact member 17, contact 15 of coder N2 and contact member 13 to the opposite terminal of battery 11. When the handle 3 of the brake valve EV is moved to the service position so as to bring the contact member 4 into engagement with the contact segment 6, a third circuit for relay 16 can be traced from battery 11 through winding of relay 16, contact member 4, contact segment 6, and to the opposite terminal of the battery 11. It follows, that with the signaling key K1 in its upper and normal position the relay 16 is energized once each cycle of the coder N1 thereby causing its armature 84 to be operated between its front contact 18 and its back contact 19 at the code frequency of sixty cycles per minute. When the signaling key K1 is depressed, the relay 16 will be energized once each cycle of the coder N2 causing its armature 84 to be operated at the code frequency of one hundred cycles per minute. When the handle 3 is moved to the service position, the relay 16 will be held steadily energized irrespective of the operation of the coders N1 and N2. With relay 16 operated in step with either of the coders N1 or N2 its front contact 18 is closed approximately one half of the time and its back contact 19 is closed approximately one half of the time. As will shortly appear the relay 16 when thus operated divides the time into transmitting and receiving periods by the closing of a transmitting circuit at its front contact 18 and by the closing of a receiving circuit at its back contact 19. Thus with the engineer's brake valve EV in any

of its operating positions, except the service position, and the signaling key K1 in its upper and normal position, the locomotive apparatus alternates between the transmitting and the receiving conditions at the code rate of sixty times per minute, and with the signaling key K1 depressed, it alternates between the two conditions at the code rate of one hundred times per minute, while, when the handle 3 of the brake valve EV is moved to the service position, the locomotive apparatus is held steadily in the transmitting condition.

20 and 21 are inductor coils located on the locomotive in inductive relation with the traffic rails 1 and 1^a, respectively. By means of these inductor coils 20 and 21 energy is transmitted to and received from the traffic rails by the locomotive apparatus, and to this end they are alternately connected to the transmitting circuit and the receiving circuit by the operation of the relay 16 as will shortly appear.

On the locomotive there are provided three generators G, G1 and G2 adapted to supply carrier current at different frequencies such, for example, as two thousand, two thousand twenty, and two thousand thirty cycles per second, respectively. Since the specific type of these generators forms no part of my invention, they are shown conventionally only in the drawings. The symbol G indicates apparatus by means of which current of a carrier frequency of two thousand can be obtained, and likewise symbols G1 and G2 indicate apparatus by means of which current of the carrier frequencies of two thousand twenty, and two thousand thirty, respectively, can be obtained. The output of these generators is delivered to a power amplifier PA. The output of generator G is connected directly to the input of the power amplifier. The output of generator G1 is connected to the input of the amplifier over wire 22, contact segment 8, contact member 5 when handle 3 occupies either the lap or the service position, wire 23, power amplifier PA and wire 24 to the other output terminal of generator G1. The output of generator G2 is connected to the input of power amplifier PA over wire 25, contact segment 7, contact member 5 when handle 3 occupies either the release or the running position, wire 23, power amplifier PA, and wires 24 and 26 to the opposite terminal of generator G2. The power amplifier PA amplifies the current received from the generators G, G1 and G2 and delivers it to the inductor coils 20 and 21 over the transmitting circuit. This transmitting circuit can be traced from the right-hand output terminal of power amplifier PA through wire 27, coils 21 and 20 in series, wire 28, armature 84 of relay 16, front contact 18 and wire 29 to the left-hand output terminal of power amplifier PA. Thus, with the handle 3 of the brake valve EV moved to either the release or the running position the coils 20 and 21 are supplied, each time the relay 16 is energized to close its front contact 18, with an impulse of carrier current of the combined frequencies of two thousand and two thousand thirty which produces the effect of a carrier frequency of two thousand modulated at thirty cycles. When the handle 3 occupies either the lap of the service position, an impulse of carrier current of the combined frequencies of two thousand and two thousand twenty, producing the effect of a carrier current of the frequency of two thousand modulated at twenty cycles, is supplied to the coils 20 and 21 each time the relay 16 is picked.

up. When the handle 3 occupies the service position and the relay 16 is held steadily energized, coils 20 and 21 are continuously supplied with current of the combined frequencies of two thousand and two thousand twenty, producing the effect of a continuous impulse of carrier current of the frequency of two thousand modulated at twenty cycles. When the handle 3 occupies the emergency position, the impulses supplied to the coils 20 and 21 contain the single carrier frequency of two thousand, giving the effect of a non-modulated carrier current of the frequency of two thousand. The code frequency of the impulses supplied to the coils 20 and 21 will be sixty per minute when the signaling key K1 occupies its upper and normal position causing the coder N1 to be active, and the code frequency will be one hundred per minute when the signaling key K1 is depressed causing the coder N2 to be active. As stated above, when the handle 3 occupies the service position, the relay 16 is held steadily energized and thus the current supplied to the coils 20 and 21 is non-coded. The power amplifier PA may be any one of a number of types among them being the vacuum tube type. As the specific type of this power amplifier forms no part of my invention, it is shown conventionally only in order to simplify the drawings. It will be understood that my invention is not limited to the frequencies of two thousand, two thousand twenty, and two thousand thirty for the carrier currents, nor to the code frequencies of sixty and one hundred, and that these frequencies are given by way of illustration only as other frequencies could equally well be selected should it seem desirable to do so.

Referring to Fig. 2, 30 and 31 are inductor coils similar to the coils 20 and 21, and these coils 30 and 31 are mounted at the caboose in inductive relation with the traffic rails 1 and 1^a, respectively. The inductor coils 30 and 31 are connected either to a receiving circuit or to a transmitting circuit of Fig. 2 in the following manner. With the apparatus of Fig. 2 all deenergized the coils 30 and 31 are connected to the receiving circuit which can be traced from the right-hand terminal of coils 30 and 31 through wire 32, input side of a filter F1 to be referred to later, wire 33, back contact 34 of a relay 35 to be described later and wire 36 to the left-hand terminal of coils 30 and 31. Under conditions to be described later this receiving circuit is at times completed by the path that branches from wire 33 through the front contact 37 of a relay 38 to be referred to later, and thence by the wire 36 to the left-hand terminal of coils 30 and 31. Under the condition of relay 35 being picked up to close its front contact 39 and the relay 38 being deenergized to close its back contact 40, as will appear when the operation of the system is described, the coils 30 and 31 are connected to the transmitting circuit, which can be traced from the right-hand terminal of the coils along wires 32 and 41, output of a power amplifier PA, wire 42, front contact 39 of relay 35, back contact 40 of relay 38 and thence by the wire 36 to the left-hand terminal of the coils 30 and 31.

The filter F1 is a band pass filter of any one of several well-known types and is so proportioned and adjusted as to pass current of the range of the frequencies of generators G, G1 and G2 on the locomotive, to the input of an amplifier AM with relatively low attenuation but offering a relatively high attenuation to frequencies

above or below the limits of two thousand and two thousand thirty cycles per second. The amplifier AM is preferably of the vacuum tube type so arranged and proportioned as to amplify the current of the carrier frequencies received through the filter F1 and to detect and deliver in its output circuit current of the modulation frequency of the carrier current received. As the specific type of the band pass filter F1 and the amplifier AM form no part of my invention, they are shown conventionally only in the drawings.

Part of the output current delivered by the amplifier AM is fed to a relay 43 through a full wave rectifier 45. This circuit being non-tuned the relay 43 will, therefore, respond to any modulation frequency appearing in the output of amplifier AM. The remainder of the output of the amplifier AM is applied to a relay 46 through a high pass filter F2 and a full wave rectifier 47. The high pass filter F2 may be of different type but preferably is of the form including condensers 44, 44^a and 44^b in series and inductances 93 and 93^a in shunt with the circuit in the usual manner. The parts of this filter are so proportioned and adjusted as to pass current of a frequency above twenty-five cycles per second and to substantially prevent the passage of all current below the cut-off frequency of twenty-five cycles per second. From what has just been said, it is clear that relay 46 will be energized when the output current of amplifier AM contains the modulation frequency of thirty cycles per second but will not be energized when the modulation is twenty cycles per second. That is to say, relay 43 will be operated in response to code impulses of carrier current applied to the input of the amplifier AM when the modulation frequency is either twenty or thirty cycles per second, but the relay 46 will be operated only when the carrier current is modulated at a frequency above the cut-off frequency of the high pass filter F2, which in this instance is twenty-five cycles per second.

The relay 43 controls over its front contact 48 a simple circuit for energizing the relay 38, and the relay 46 controls over its front contact 49 a simple circuit for energizing a relay 50 as will be readily understood by an inspection of Fig. 2. Thus with code impulses of modulated carrier current picked up from the traffic rails 1 and 1^a by the coils 30 and 31 the relay 43, and in turn the relay 38, will be operated at the code frequency of the impulses. When the modulation frequency is above the cut-off frequency of twenty-five cycles per second, the relay 46 will also be operated to energize the relay 50 which is slow-releasing in character and will thus remain picked up from one code impulse to the next.

Operating the relay 38 causes current to be alternately supplied to the two halves of the primary winding 51 of a transformer T, the circuit being completed from the terminal B of the current source through the top half of the winding 51 and to the terminal C of the current source, when the front contact 52 of relay 38 is closed, and completed through the bottom half of the primary 51 when the back contact 53 is closed. This alternate energizing of the two halves of primary 51 of transformer T induces an alternating voltage in the secondary windings 54 and 55 of transformer T, the frequency of which alternating voltage will correspond to the frequency at which relay 38 is operated, that is, a frequency corresponding to the code rate of the impulses. The output of secondary 55 is supplied to a relay 56 through a full wave rectifier 57. Relay 56

56 is slow-releasing in character and will thus retain its front contacts 58 and 59 closed whenever the relay 38 is operated at either the code frequency of sixty or one hundred per minute but 5 will be released when relay 38 is held steadily energized or when it is deenergized for any length of time. The circuit for the secondary 54 includes a condenser 62 and a reactor 61 in series. A portion of reactor 61 is connected to the winding of a relay 63 through a full wave rectifier 64. The parts of this circuit supplied by the secondary 54 are so proportioned and adjusted that the relay 63 is energized when the relay 38 is operated at the code frequency of one hundred cycles 10 per minute only.

15 The relay 38 controls over its front contact 65 a simple circuit for energizing the relay 35. As previously pointed out, the receiving circuit is completed through either the front contact 37 20 of relay 38 or the back contact 34 of relay 35 and the transmitting circuit for the apparatus of Fig. 2 is completed through the front contact 39 of relay 35 and back contact 40 of relay 38 in series. Thus when an impulse of modulated carrier current 25 is picked up by the coils 30 and 31 to operate the relay 43, and, in turn, the relay 38, the receiving circuit is held closed at the front contact 37 as long as the impulse lasts. At the termination 30 of such incoming impulse, the relay 38 immediately drops to close its back contact 40 but relay 35 remains picked up for a period as it is slow-releasing in character, and thus during its release period, the inductor coils 30 and 31 are connected to the transmitting circuit described hereinbefore. At the end of its release 35 period, the relay 35 drops to open the transmitting circuit at its front contact 39 and to again close the receiving circuit at its back contact 34. It will be understood that the release period of 40 relay 35 is made less than one-half cycle of either coder N1 or N2 on the locomotive. It follows that the receiving circuit of Fig. 2 is closed at all times except for a period immediately following the termination of an incoming impulse of modulated carrier current, at which time the transmitting circuit is closed during the release period of the relay 35 which period in any event is less than one-half cycle of the active coder on the locomotive.

45 50 The caboose is equipped with an auxiliary brake controlling mechanism which includes a main reservoir MR, a feed valve FV and three electropneumatic valves DR, DE and DS. The caboose, of course, will also be equipped with a compressor, air gages and all other equipment necessary to insure ample supply of air pressure in its main reservoir MR independently of the usual supply of air pressure on the locomotive. The valves DR and DS are biased to the closed 55 position and are lifted to the open position when the associated magnets 68 and 69, respectively, are energized. The valve DE is biased to the open position and is held closed when its associated magnet 70 is energized. When valve DR is open, due to its magnet 68 being energized, the main reservoir MR is connected to the train brake pipe, indicated by the reference character BP, through the feed valve FV, and the auxiliary brake controlling mechanism in the caboose reproduces the running condition of the engineer's 60 brake valve EV on the locomotive. When the valve DS is open, due to its magnet 69 being energized, the train brake pipe BP is connected to the atmosphere through a vent of such characteristics as to effect the service application of

the train brakes. When the valve DE is open, due to its magnet 73 being deenergized, the brake pipe BP is connected to the atmosphere through a vent of such characteristics as to effect an emergency application of the brakes. When the valve DE is held closed, due to its magnet 70 being energized, and both valves DR and DS are closed, due to their respective magnets being deenergized, the supply and the exhaust of the brake pipe BP are both blanked and the auxiliary brake controlling mechanism reproduces the lap condition of the engineer's brake valve EV. In the form of apparatus shown in Fig. 2, the magnet for the emergency valve DE is the one normally held energized to insure the closed circuit principle for my system. It will be understood, however, that the magnet of either of the other two valves could be so employed should it seem desirable to do so.

90 Whenever both relays 56 and 50 are picked up in a manner to appear later, current is supplied to the magnet 68 of valve DR by a circuit which extends from the terminal B of the current source through winding of magnet 68, wire 71, front contact 72 of relay 50, front contact 58 of relay 56 95 and to the opposite terminal C of the source of current. With relay 56 picked up, the magnet 70 of valve DE is supplied with current from the terminal B of the current source through winding of the magnet 70 and the front contact 59 of relay 56 to the terminal C of the current source. In the event the relay 35 is held steadily energized and both relays 50 and 56 are deenergized, the magnet 69 of valve DS will be energized by current flowing from the terminal B of the current source through winding of magnet 69, back contacts 73 and 74 of relays 50 and 56, respectively, and front contact 66 of relay 35 to the terminal C, to open the valve DS. At such a time, that is, when relay 35 is held steadily energized, the magnet 70 of valve DE will be energized by the circuit that includes the front contact 67 of relay 35. The caboose is provided with a signaling device 75 the function of which will appear later, and which may be either a lamp 100 or a magnet. The signaling device 75 is provided with a circuit that extends from the terminal B of the current source through the lamp 75 and the front contact 76 of relay 63 to the opposite terminal C.

105 125 As stated earlier in the specification, the caboose apparatus is adapted to at times transmit an indication influence. It has been pointed out in detail hereinbefore how the coils 30 and 31 on the caboose are connected to a transmitting 110 circuit which includes the output of the power amplifier PA, during the release period of relay 35 immediately following the termination of an incoming impulse. The caboose is provided with three generators of carrier frequency current G, 115 G1 and G2. These generators are preferably similar to the corresponding generators on the locomotive. That is to say, generator G of Fig. 2 delivers carrier current of the frequency of two thousand cycles per second, generator G1 delivers 120 carrier current at the frequency of two thousand twenty, and generator G2 at the frequency of two thousand thirty. The power amplifier PA of Fig. 2 is also preferably similar to the power amplifier PA of Fig. 1 and this power amplifier in 125 the caboose receives the current from the generators G, G1 and G2 and delivers it to the coils 30 and 31 through the transmitting circuit. The output of the generator G is applied directly to the input of the power amplifier PA, while the 130

output of the generator G1 is applied to the input of power amplifier PA over a circuit that can be traced from the lower terminal of generator G1 through wire 77, contact 78 of a signaling key K2, wire 79, contact 80 operated by the valve DE and closed only when that valve is closed, wire 81, input of amplifier PA and wire 82 to the upper terminal of generator G2. The output circuit for the generator G2 includes wire 83, contact 78 of signaling key K2 when depressed and thence by wire 79, front contact 80, wire 81, input of amplifier PA and wire 82. It follows that with the signaling key K2 in its upper and normal position and the valve DE closed the impulses transmitted by the caboose apparatus will have the combined frequencies of two thousand and two thousand twenty giving the effect of an impulse of carrier current of the frequency of two thousand having a modulation frequency of twenty cycles. When the signaling key K2 is depressed and valve DE closed, the transmitted impulses from the caboose apparatus will have the combined frequencies of two thousand and two thousand thirty giving the effect of a carrier current of the frequency of two thousand modulated at thirty cycles.

Referring again to Fig. 1, the locomotive is provided with a receiving circuit that can be traced from the right-hand terminal of coils 20 and 21 through wires 27 and 99, filter F1, back contact 19 of relay 16, and wire 28 to the left-hand terminal of the coils 20 and 21. The filter F1 is a band pass filter preferably similar to the filter F1 of Fig. 2 and is so proportioned and adjusted as to pass to the input of the amplifier AM current of the range of frequencies of the generators G1, G1 and G2 in the caboose with relatively low attenuation but offering relatively high attenuation to current of frequencies either above or below these limits. The amplifier AM of Fig. 1 is preferably similar to the amplifier AM in the caboose and is adapted to amplify the current received through the filter F1 and to detect and deliver in its output circuit current of the modulation frequency of the carrier current applied to its input. A portion of the output of the amplifier AM is supplied through a full wave rectifier 85 to a relay 86. This circuit being non-tuned the relay 86 will be energized when either modulation frequency of twenty or thirty cycles per second appears in the output of the amplifier AM. Relay 86 is slow-releasing in character and will remain picked up when the incoming impulses are coded at the rate of either sixty or one hundred cycles per minute. The relay 86 controls at its front contact 87 a simple circuit to an indicating lamp 88. The remaining portion of the output of amplifier AM is applied to a relay 89 by a circuit that includes a high pass filter F2 and a full wave rectifier 90. The filter F2 of Fig. 1 is preferably similar to the high pass filter F2 in the caboose and as here shown includes condensers 94, 94^a and 94^b in series and the two inductances 95 and 95^a in shunt with the circuit. The parts of this filter F2 are so proportioned and adjusted as to pass current of a frequency above twenty-five cycles per second and to substantially prevent the passage of all current below this cut-off frequency of twenty-five cycles. It follows that relay 89 will be energized to close its front contact 91 when the output of amplifier AM is of the modulation frequency of thirty cycles per second but not when the output is of the modulation frequency of twenty cycles per second. Relay 89 is slow-releasing in character to retain

its front contact 91 closed from one code impulse to the next. Relay 89 when picked up closes a simple circuit to the signaling lamp 92.

In describing the operation of the apparatus of Figs. 1 and 2, I will first assume that the engineer's brake valve EV is in the running or release position and the signaling key K1 is in its upper and normal position. The relay 16 of Fig. 1 will thus be operated at the sixty code frequency in step with the coder N1 to alternately connect the inductor coils 20 and 21 on the locomotive to the transmitting and the receiving circuits of Fig. 1. The contact member 5, actuated by the handle 3, being now in engagement with the contact segment 7, the input of the power amplifier PA is supplied with carrier current of both the frequencies two thousand and two thousand thirty, and thus as the relay 16 picks up to close the transmitting circuit, an impulse of carrier current containing the two frequencies two thousand and two thousand thirty, producing in effect a carrier current of the frequency of two thousand modulated at thirty cycles, is supplied to the traffic rails 1 and 1^a. This impulse is picked up by the coils 30 and 31 at the caboose and applied to the input of the amplifier AM through the band pass filter F1 inasmuch as the receiving circuit is now closed at the back contact 34 of relay 35. This impulse having the modulation frequency of thirty causes both relays 43 and 46 to be energized. The relay 43 on being picked up causes relay 38 and in turn relay 35 to be energized, while the picking up of relay 46 causes relay 50 to be energized. As relay 35 picks up, the receiving circuit is opened at the back contact 34 but this circuit is now closed at the front contact 37 of relay 38 and thus the receiving circuit in the caboose is held closed as long as the impulse lasts. As the coder N1 next swings its contact member 9 to the left and causes relay 16 to drop, the outgoing impulse is terminated and the coils 20 and 21 are transferred to the receiving circuit. The termination of the impulse transmitted from the locomotive causes the relays 43, 46 and 38 in the caboose to immediately drop but the relays 35 and 50 remain picked up for a period due to their slow-releasing characteristics. With relay 38 down and relay 35 up, the transmitting circuit of Fig. 2 is closed at the back contact 40 of relay 38 and the front contact 39 of relay 35.

Operating the relay 38 at the sixty code frequency causes the relay 56 to be picked up and as relay 50 is now also up, the magnet 68 of valve DR is supplied with current over the front contacts 72 and 58 of relays 50 and 56, respectively, and the magnet 70 of valve DE is supplied with current over the front contact 59 of relay 56. As the valve DR is now open and the valves DE and DS are both closed, the auxiliary brake controlling mechanism establishes the running condition of the train brakes. The closing of the valve DE closes in turn the contact 80 so that the input of the power amplifier PA in the caboose is now supplied with carrier current of the two frequencies two thousand and two thousand twenty. The transmitting circuit being now held closed by the relay 35, an impulse from the power amplifier PA containing the carrier frequencies two thousand and two thousand twenty is supplied to the traffic rails 1 and 1^a. This return impulse transmitted from the caboose apparatus during the slow release period of relay 35 gives the effect of an impulse of carrier current of a frequency of two thousand modulated at twenty

cycles and thus when picked up by the coils 20 and 21 on the locomotive and applied to the input of the amplifier AM through the band pass filter F1 causes the relay 86 to be energized but 5 will not affect the relay 89 due to the high pass filter F2. With relay 86 energized the indication lamp 88 is displayed to the locomotive operator to indicate that the auxiliary brake controlling mechanism in the caboose has responded to the 10 running code impulse transmitted from the locomotive. As long as the handle 3 of the brake valve EV remains in the running position there will be alternately exchanged between the locomotive and the caboose apparatus impulses of 15 modulated carrier current to hold the auxiliary brake controlling mechanism in the running position and to display the indication lamp 88 on the locomotive.

I will next assume that the handle 3 of the 20 brake valve EV is moved to the lap position where the contact member 5 engages the contact segment 8 and the input of the power amplifier PA of Fig. 1 is made to contain carrier current of the two frequencies two thousand and two thousand 25 twenty giving in effect a carrier current of the frequency of two thousand modulated at twenty cycles. The signaling key K1 still remaining in its upper and normal position, code impulses of current having the effect of a carrier current of 30 the frequency of two thousand modulated at twenty cycles will be now transmitted from the locomotive each time the relay 16 is picked up. At the caboose, the receipt of an impulse of carrier current modulated at twenty cycles causes 35 the relay 43 in the output of the amplifier AM to be operated the same as described under the running condition, but the relay 46 will be now deenergized due to the high pass filter F2 preventing the passage of the modulation frequency 40 of twenty cycles and the relay 50 will be in turn released. Operating the relay 43 causes the relays 38 and 35 to be operated in the same manner as hereinbefore described to transfer the caboose apparatus between the receiving and 45 transmitting conditions in step with the locomotive apparatus, and also to retain the relay 56 picked up. As relay 50 releases, the magnet 68 is deprived of current and valve DR will be closed. Relay 56 still being picked up, the magnet 70 of 50 the valve DE is retained energized to hold valve DE closed. Thus, all three valves DR, DE and DS of the auxiliary mechanism are now closed and the auxiliary mechanism reproduces the lap condition established by the valve EV on the locomotive. Contact 80 still being held closed, 55 impulses containing both the carrier frequencies two thousand and two thousand twenty, giving the effect of a carrier current of the frequency of two thousand modulated at twenty cycles, are still transmitted from the caboose, which cause the indication lamp 88 on the locomotive to be displayed in the same manner as pointed out under the running condition of the brake valve EV. Thus as long as the handle 3 is retained at the lap position, impulses are exchanged between the locomotive and the caboose apparatus at the code frequency of sixty cycles per minute, the impulses transmitted from the locomotive containing the two carrier frequencies of two thousand and two thousand twenty and the impulses returned from the caboose to the locomotive also containing the two frequencies two thousand and two thousand twenty. The exchange of these 70 impulses cause the auxiliary brake controlling

mechanism to be held in the lap position and the indication lamp 88 to be displayed.

In the event the handle 3 of valve EV is moved to the service position, contact member 5 still engages the contact segment 8 and the input of the power amplifier PA of Fig. 1 contains both the carrier frequencies two thousand and two thousand twenty the same as under the lap position of handle 3. The contact member 4, however, now engages the contact segment 6 and the relay 16 is held steadily energized and the transmitting circuit held continuously closed so that there is now continuously transmitted from the locomotive current having the effect of a carrier current of the frequency of two thousand modulated at twenty cycles. At the caboose, the continuous receipt of energy in the form of a carrier current of the frequency of two thousand modulated at twenty cycles causes the relays 43, 38 and 35 to be held continuously energized and the relays 46, 56, 63 and 50 all to be deenergized. The magnet 70 of valve DE is now controlled by the circuit that includes the front contact 67 of relay 35 and the magnet 69 of valve DS is supplied with current over the back contacts 100 73 and 74 of relays 50 and 56, respectively, and the front contact 66 of relay 35. With valves DR and DE both closed and valve DS opened the auxiliary brake controlling mechanism establishes a service application of the train brakes. 105 The transmitting circuit for the caboose apparatus is now held continuously open due to both relays 38 and 35 being held continuously energized and thus no return impulses are transmitted to the locomotive apparatus and the relay 110 36 is released to extinguish the indication lamp 88.

With the handle 3 of valve EV moved to the emergency position, the relay 16 is operated at the code frequency of 60 cycles per minute but only generator G is now active to supply carrier 115 current to the input of the power amplifier PA and the impulses transmitted from the locomotive apparatus are non-modulated current of the frequency of two thousand, with the result that neither relay 43 nor relay 46 of the caboose apparatus is energized. The deenergized condition of both relays 43 and 46 cause in turn the relays 38, 35, 56, 63 and 50 to all become deenergized and the magnets 68, 69 and 70 all to be deprived of current. Deenergizing magnet 70 permits 120 the valve DE to be opened and the auxiliary brake controlling mechanism to produce an emergency application of the train brakes. Relays 38 and 35 not now being operated no return 125 impulses are transmitted from the caboose and thus both relays 86 and 89 on the locomotive are deenergized.

Under the running and the lap positions of the valve EV the operator on the locomotive can signal to the crew on the caboose by depressing 130 the signaling key K1 for long or short intervals in accordance with a prearranged code. The depressing of the signaling key K1 causes the relay 16 to be operated in step with the coder N2, that is, the code frequency of the code impulses transmitted from the locomotive is changed from sixty cycles to one hundred cycles per minute while the modulation of the impulses remains the same. Operating the relay 140 43 and in turn the relay 38 of Fig. 2 at the code frequency of one hundred cycles per minute causes both relays 56 and 63 to be energized. The relays 56 and 50 will now be active to control the magnets 68 and 70 the same as described hereinbefore, while the picking up of the relay 145 150

63 in step with the intervals during which the signaling key K1 is held depressed causes the signal lamp 75 to be flashed in accordance with the code at which key K1 is operated and the 5 code message is thus displayed to the caboose crew. In the event the crew in the caboose desires to signal to the operator on the locomotive they can do so by depressing the signaling key K2 for long or short intervals in accordance 10 with the prearranged code. The depressing of signaling key K2 causes the input for the power amplifier PA of Fig. 2 to contain the two carrier frequencies, two thousand and two thousand thirty, assuming, of course, that the valve DE 15 is held closed to close the contact 80. The return impulses now give the effect of a carrier current of a frequency of two thousand modulated at thirty cycles. On the locomotive the high pass filter F2 in the output of the amplifier 20 AM passes the thirty cycle modulation current with the result that both relays 86 and 89 are energized. Relay 86 controls the indication lamp 83 in the same manner as hereinbefore described while the picking up of the relay 89 causes the 25 display of the signaling lamp 92 and thus the lamp 92 will be flashed in accordance with the code at which the signaling key K2 in the caboose is operated.

In Fig. 3 there is disclosed a modified form of 30 apparatus that may be employed in the output circuit of the amplifier AM. In this form of apparatus the high pass filter F2 is replaced by a low pass filter F3. This low pass filter F3 may take any one of several forms but as here 35 shown consists of inductances 96, 97 and 98 in series, and the condensers 101 and 102 in shunt with the circuit supplying current to the relay 46 through the rectifier 47. The parts of this low 40 pass filter F3 are so proportioned and adjusted as to have a cut-off frequency of twenty-five cycles, that is to say, this filter passes with relatively small attenuation current having frequencies under twenty-five cycles per second but will offer a relatively high attenuation to all currents 45 having a frequency above the cut-off frequency of twenty-five cycles. From the foregoing description it is apparent that the relay 46 of the apparatus of Fig. 3 will be energized whenever the carrier current contains the two frequencies 50 two thousand and two thousand twenty and will be deenergized when the carrier current contains the two frequencies two thousand and two thousand thirty. By substituting the low pass filter F3 of Fig. 3 having a cut-off frequency of twenty- 55 five cycles for the high pass filter F2 of Fig. 2 also having a cut-off frequency of twenty-five cycles and by choosing the proper combinations of the generators G, G1 and G2 so that in one condition the combined carrier currents give the 60 effect of a carrier current of a frequency of two thousand modulated at twenty cycles and under other conditions the combined carrier currents give the effect of a carrier current of the frequency of two thousand modulated at thirty 65 cycles, the two relays 43 and 46 will control the auxiliary brake controlling mechanism in the same manner as in Fig. 2. Furthermore, the substitution of a low pass filter F3 for the high pass filter F2 of Fig. 1 will cause the locomotive apparatus to produce the same operation of the relays 70 86 and 89 as obtained for Fig. 1.

Although I have herein shown and described only certain forms of apparatus embodying my invention, it is understood that various changes 75 and modifications may be made therein within

the scope of the appended claims without departing from the spirit and scope of my invention.

Having thus described my invention, what I claim is:

1. Apparatus for the control of train brakes comprising in combination with the usual engineer's brake valve on the locomotive, an auxiliary brake controlling mechanism at another point on the train capable of reproducing a brake applying and a brake releasing condition of the engineer's brake valve, sources of carrier current having different frequencies, means governed by the engineer's brake valve for combining a first source of said sources with a second source or combining the first source with the third source to produce the effect of a carrier current having one modulation frequency for the brake applying condition and having a second modulation frequency for the brake releasing condition, an electroresponsive means influenced by said carrier current, an output circuit including a filter having a cut-off frequency midway between the two modulation frequencies governed by said electroresponsive means, and a relay controlled by said output circuit for causing the auxiliary 80 brake controlling mechanism to register with the condition of the engineer's brake valve.

2. A control system for railway trains including, a brake controlling mechanism capable of establishing different conditions of the train 105 brakes, a plurality of generators of carrier current of different frequencies, a manually controlled means having different positions for combining the output of a first generator of said generators with that of a second, or combining the 110 output of the first generator with that of the third and thereby produce the effect of a carrier current having either a first or a second modulation frequency, an electroresponsive means influenced by the carrier current, an output circuit 115 including a high pass filter having a cut-off frequency between the first and second modulation frequencies governed by said electroresponsive means, and means controlled by said output circuit for causing the brake controlling mechanism to establish the brake condition corresponding to the position of the manually controlled means.

3. Apparatus for the control of train brakes comprising in combination with the usual engineer's brake valve on the locomotive, an auxiliary brake controlling mechanism at another point on the train capable of reproducing a first and a second condition of the engineer's brake valve, an electroresponsive means having an input circuit including a band pass filter adapted to pass currents within a given frequency range, an output circuit including a filter having a predetermined cut-off frequency for said electroresponsive means and selectively responsive to frequencies above and below the cut-off frequency for causing the auxiliary mechanism to establish the first or the second condition, three sources of current of different frequencies within said frequency range and with a frequency difference, 125 between a first and a second of said sources less than said cut-off frequency and a frequency difference between said first source and the third source greater than said cut-off frequency, means controlled in accordance with the position of the 130 engineer's brake valve for combining the first and the second sources or combining the first and the third sources to give the effect of a current modulated at a frequency below the cut-off frequency or modulated at a frequency above the 135 140 145 150

cut-off frequency, and means to impress the combined currents upon the electroresponsive means whereby the auxiliary mechanism is made to register with the position of the engineer's brake valve.

4. A control system for railway trains including, an electroresponsive means on the train selectively responsive to different modulation frequencies of an alternating current, a first output circuit for said electroresponsive means including a high pass filter having a predetermined cutoff frequency, a first relay controlled by said first output circuit, a second output circuit for said electroresponsive means not including a filter, a second relay controlled by said second output circuit, control means having one position for supplying alternating current modulated at a frequency above said predetermined cutoff frequency and a second position for supplying alternating current modulated at a frequency below said cutoff frequency, means for impressing the current from said control means upon said electroresponsive means whereby said first and second relays are selectively controlled, and a controlling mechanism jointly controlled by said relays.

5. A control system for railway trains including, current sources at one point on a train adapted to supply alternating current modulated at a first or a second modulation frequency, an electroresponsive means at another point on the train responsive to modulated alternating current, a relay, an output circuit for said electroresponsive means for controlling said relay and which includes a high pass filter having a cut-off frequency between said first and second modulation frequencies whereby current is passed to said relay in response to alternating current of the second modulation frequency only, a controlling mechanism governed by said relay, and means to at times impress current from said sources modulated at said second modulation frequency upon the electroresponsive means for governing said controlling mechanism.

6. A control system including, a first and second station interconnected by a communicating circuit, three generators of carrier current of different frequencies at each station, manually controlled means at the first station to combine the output of different pairs of its generators to form a first or a second frequency difference, transmitting means at the first station to periodically supply said combined output to the circuit, a demodulating means at the second station periodically connected with the circuit to receive and demodulate the current supplied at the first station, a first output circuit for the demodulator including a filter having a cut-off frequency midway between said first and second frequency difference, a second output circuit for said demodulator and non-tuned, an operating mechanism controlled by said output circuits, means governed in part by the operating mechanism to combine the output of different pairs of the generators at said second station to form a first and a second frequency difference, transmitting means at the second station to periodically supply the combined output of its generators to the communicating circuit, a receiving and demodulating means at the first station periodically connected with the communicating circuit to receive and demodulate the current supplied at the second station, a first output circuit for said demodulator including a filter having a cut-off frequency midway between the two frequency differences of the second station, a second output circuit for said demodulator and

non-tuned, indicating means at the first station controlled by its output circuits, and synchronizing means for governing the transmitting and receiving means at each station whereby a continuous two way control is obtained between the two stations.

7. A control system including, a first and a second station interconnected by a communicating circuit, three generators of carrier current of different frequencies at the first station; manually controlled means at the first station having a first position to combine and code the output of a particular pair of the generators to form a first coded frequency difference, a second position to combine and code the output of a different pair of the generators to form a second coded frequency difference and a third position to combine only the output of the last mentioned pair of generators to form a non-coded frequency difference; means at the first station to supply said output of the generators to said circuit, receiving and demodulating means at the second station connected with said circuit, a first output circuit for the demodulator and including a filter having a cut-off frequency midway between said first and second frequency differences, a relay controlled by said output circuit, a second output circuit for said demodulator and non-tuned, decoding means controlled by said second output circuit, and operating mechanism having three different positions and selectively controlled by said relay and said decoding means to cause said mechanism to register with the position of the manually controlled means.

8. A control system including, a first and a second station interconnected by a communicating circuit, three generators of carrier current of different frequencies at the first station, manually controlled means to combine the output of a particular pair of the generators to form a first frequency difference and a second position to combine the output of a different pair of the generators to form a second frequency difference, means at the first station to supply said output of the generators to said circuit, receiving and demodulating means at the second station connected with the circuit, a first and a second control relay, a non-tuned output circuit receiving current from the demodulator for controlling one of the relays, a tuned circuit receiving current from the demodulator for controlling the other of said relays and including a filter having a cut-off frequency midway between said frequency differences whereby relatively large variations of the frequency differences may be tolerated without a loss of control.

9. Apparatus for the control of train brakes comprising in combination with the usual engineer's brake valve on the locomotive, an auxiliary brake controlling mechanism at another point on the train capable of reproducing different conditions of the engineer's brake valve, three generators of carrier current of different frequencies on the locomotive, means governed by one position of the engineer's brake valve for combining the output of a particular pair of said generators to form a first frequency difference, means governed by a second position of the engineer's brake valve for combining the output of a different pair of the generators to form a second frequency difference, means for supplying the output of said generator to the traffic rails, receiving and demodulating means at said other point and inductively coupled with the traffic rails to receive the current transmitted

- from the locomotive, a pair of control relays, a non-tuned circuit receiving current from the demodulator to control one relay, a tuned circuit receiving current from the demodulator to control the other relay and including a filter having a cut-off frequency midway between said frequency differences, and means controlled by said relays for causing the auxiliary mechanism to register with the engineer's brake valve.
10. Apparatus for the control of train brakes comprising in combination with the usual engineer's brake valve on the locomotive, an auxiliary brake controlling mechanism at another point on the train capable of reproducing different conditions of the engineer's brake valve, three generators of carrier current of different frequencies on the locomotive; means governed by one position of the brake valve to combine and code the output of a particular pair of said generators to form a first coded frequency difference, by a second position to combine and code the output of a different pair of the generators to form a second coded frequency difference and by a third position to combine only the output of the last mentioned pair of generators to form a non-coded frequency difference; means for supplying the output of said generators to the traffic rails, receiving and demodulating means at said other point and inductively coupled with the traffic rails to receive the current transmitted from the locomotive, a decoding means, a non-tuned circuit receiving current from the demodulator to operate the decoding means, a first relay controlled by the decoding means, a tuned circuit receiving current from the demodulator and including a filter having a cut-off frequency midway between said frequency differences, a second relay controlled by the tuned circuit, and means selectively governed by said relays for causing the auxiliary mechanism to register with said engineer's brake valve.
11. Apparatus for the control of train brakes comprising in combination with the usual engineer's brake valve on the locomotive, an auxiliary brake controlling mechanism at another point on the train capable of reproducing a given condition of the engineer's brake valve, two generators of carrier current of different frequencies on the locomotive, means governed by the given position of said brake valve to combine the output of said generators to form a given frequency difference, transmitting means to periodically supply the output of said generators to the traffic rails, receiving and demodulating means at said other point and periodically coupled with the traffic rails to receive the current transmitted from the locomotive, a circuit receiving current from the demodulator and including a filter having a cut-off frequency above said frequency difference, means controlled by said circuit for causing the auxiliary mechanism to establish said given position, a pair of generators of carrier current of different frequencies at said other point, means controlled by the auxiliary mechanism for combining the output of said pair of generators to form an indication frequency difference, means to periodically supply the output of said pair of generators to the traffic rails, receiving and demodulating means at the locomotive periodically coupled with the traffic rails to receive the current transmitted from said other point, a circuit receiving current from the last mentioned demodulator and including a filter having a cut-off frequency above the indication frequency difference, an indicating device controlled by said circuit, and synchronizing means for governing the transmitting and receiving means at each point whereby a continuous two way control is obtained between the two points.
